UNITED STATES PATENT OFFICE.

JAMES HARRIS HARDY, OF CRAWFORD, MISSISSIPPI.

RAILWAY CROSSING.

1,426,292.

Specification of Letters Patent. Patented Aug. 15, 1922.

Application filed July 14, 1921. Serial No. 484,652.

To all whom it may concern:

Be it known that I, JAMES HARRIS HARDY, a resident of Crawford, in the county of Lowndes and State of Mississippi, a citizen 5 of the United States, have invented certain new and useful Improvements in Railway Crossings, of which the following is a specification.

This invention relates to a railway crossing, and has for its object to provide a readily operable mechanism, wherein there is presented a continuous set of rails for traffic moving in a given direction, the rails of the opposite set of rails so constructed as to be 15 moved laterally by the energy of the moving train to afford a sufficient clearance for the flanges of the wheels thereof.

In the accompanying drawings:

Fig. 1 is a plan view of the crossing in 20 its normal position;

Fig. 2 is a similar view thereof showing certain parts moved to give a clear track in one direction;

Fig. 3 is a transverse section on line 2—2 25 of Fig. 1.

The numeral 1 designates a supporting bed arranged at the intersection of the main line rails 2—2 and 3—3 which intersect at right-angles to each other. Arranged upon 30 the base 1 in alignment with the sets of main line rails 1—1 are a set of rail sections 4—4, while a similar set of rail sections 5—5 are arranged in alignment with the main line rails 2—2. These rail sections 35 4—4 and 5—5 are tapered as at 6 at their ends. Arranged parallel with the rail sections 4—4 and 5—5 are two sets of guard-rails 7—7 and 8—8, which are adapted to normally fill the space between the opposite 40 rail sections. Each of these guard rails are arranged in pairs, being connected together at their inner ends by a tongue and groove joint 7' and 8' respectively, and held in a normally closed position against longitudinal 45 movement by the compression-spring 9.

The numeral 10 indicates a wedge-shaped member formed integral with the rail sections 7—7 which coincide with the tapered ends of the opposite rail sections, and are 50 curved inwardly as at 11 in order that the flanges of the wheels of the moving train may engage the rail sections and cause them to move inwardly to allow the wheels to pass through. The compression springs 12 at 55 either end of the rail sections serve to normally hold the rail-guards against the rail-

sections. Stop 13 limits the inward movement of the guard-rails.

In the normal position, as disclosed in Fig. 1, the guard-rails 7—7 and 8—8 are 60 against each of the rail sections 4—4 and 5—5, the members 10—10 of the guard-rails 7—7 forming a continuation of the rail section 4—4, and the members 10'—10' forming a continuation of the rail-sections 5—5. 65

Assuming, however, that a train is passing along the main line rails 2—2 in the direction of the arrow, as disclosed in Fig. 2, the guard-rails 7—7 are moved laterally inwardly. The compression spring 9 arranged centrally thereof permits of a longitudinal movement of the guard-rail caused by the member 10 sliding laterally along the tapered end of the rail-sections 4—4 against the tension of the compression-spring 0. The 70 guard-rails 8—8, however, are not disturbed, and the member 10—10 thereof, together with the rail-sections 5—5 form a continuous rail for the moving train, the operation being just the reverse when the train 75 is passing along the opposite set of rails 1—1.

I claim:

1. In a railroad crossing-rail, each comprising a central stationary section, longitudinally movable guard-rail sections resiliently held against the stationary rail sections, each being provided with members arranged in alignment with the oppositely disposed stationary rail sections, said guard-rail sections adapted to be moved laterally by the wheels of the moving train. 85

2. In a railroad crossing-rail, each comprising a central stationary section, divided longitudinally movable guard rail sections 90 arranged parallel with and resiliently held against the stationary rail sections, each divided section being provided with members arranged in alignment with the stationary rail sections arranged at an angle to the first-mentioned stationary section, said guard rail sections adapted to be moved both longitudinally and laterally by the wheels of the moving train. 95

3. In a railroad crossing rail, each comprising a central stationary section having tapering ends, divided laterally and longitudinally movable guard rail sections arranged parallel with the stationary rail sections, and provided at each end with tapering members arranged in alignment with the ends of the oppositely disposed rail sections, 100 105 110

2
resilient means normally holding said divided guard rail sections against longitudinal and lateral movement, and means co-operating with the moving train whereby the 5 divided guard-rail sections are moved both longitudinally and laterally to provide a passage-way for the wheels of the train.

4. In a railroad crossing rail, each comprising a central stationary section having 10 tapering ends, divided laterally and longitudinally movable guard rail sections arranged parallel with the stationary rail sections and provided at each end with tapering members arranged in alignment with the ends of the 15 oppositely disposed rail sections, resilient means normally holding said divided guard rail sections against longitudinal and lateral movement, the other ends of said divided guard rail sections adapted to be bent inwardly and to be engaged by the flanges of the 20 wheels of the moving train, whereby the guard-rail sections are moved both laterally and longitudinally to effect a clearance space between them and the stationary rail sections. 25

5. In a railroad crossing comprising a plurality of stationary rail sections having tapering ends, a plurality of divided laterally and longitudinally movable guard-rail

sections arranged parallel with the stationary rail sections, each end provided with tapering members arranged in alignment with the oppositely disposed sets of stationary rail sections, resilient means for normally holding the divided guard-rail sections together and the tapering members in alignment with the ends of the stationary rail sections, additional resilient means for normally holding the guard-rail sections against the stationary rail sections, the ends of said 40 guard rail sections being bent inwardly upon the stationary rail sections and adapted to be engaged by the flanges of the wheels of the moving train, whereby the guard rail sections are moved both laterally and longitudinally to effect a clearance space between them and the stationary rail sections. 45

6. A noiseless railroad crossing comprising a plurality of L-shaped main track rails, a plurality of L-shaped inner rails interposed between said main rails, and inner rails, the adjacent ends of said inner rails being notched out to permit of adjustment, and resilient means for holding the several parts in operative position. 50

In testimony whereof I hereunto affix my signature.

JAMES HARRIS HARDY.
